(57) **CLAIM**

The ornamental design for a handleset grip, as shown and described.

DESCRIPTION

FIG. 1 is a perspective view of a handleset grip showing our new design;

FIG. 2 is a front view of the new design for a handleset grip; FIG. 3 is a top view of the new design for a handleset grip; FIG. 4 is a bottom view of the new design for a handleset grip;

FIG. 5 is a right side view of the new design for a handleset grip, the left side view being a mirror image; and,

FIG. 6 is a back view of the new design for a handleset grip. The broken lines in the Figures are for illustrative purposes only and form no part of the claimed design.
